HELMET

Vladimir A. d'Arbeloff, Riverside, Conn.

Application March 19, 1953, Serial No. 24,122

Term of patent 7 years

(Cl. D3—13)

To all whom it may concern:

Be it known that I, Vladimir A. d'Arbeloff, a citizen of the United States, residing in Riverside, in the county of Fairfield and the State of Connecticut, have invented a new, original, and ornamental Design for a Helmet, of which the following is a specification, reference being had to the accompanying drawing forming a part hereof.

The side of the helmet opposite to that shown in Figure 1 presents a substantially similar appearance as the side shown in Figure 1.

I claim:

The ornamental design for a helmet, substantially as shown and described.

VLADIMIR A. D'ARBELOFF.
